CLAIM

The ornamental designs for a pivotal nose pad, as shown and described.

DESCRIPTION

FIG. 1 is a first perspective view of a pivotal nose pad shown in a first embodiment;

FIG. 2 is a second perspective view of the pivotal nose pad of FIG. 1;

FIG. 3 is a front elevation view of the pivotal nose pad of FIG. 1;

FIG. 4 is a rear elevation view of the pivotal nose pad of FIG. 1;

FIG. 5 is a left side elevation view of the pivotal nose pad of FIG. 1;

FIG. 6 is a right side elevation view of the pivotal nose pad of FIG. 1;

FIG. 7 is a top plan view of the pivotal nose pad of FIG. 1;

FIG. 8 is a bottom plan view of the pivotal nose pad of FIG. 1;

FIG. 9 is a first perspective view of a pivotal nose pad shown in a second embodiment;

FIG. 10 is a second perspective view of the pivotal nose pad of FIG. 9;

FIG. 11 is a front elevation view of the pivotal nose pad of FIG. 9;

FIG. 12 is a rear elevation view of the pivotal nose pad of FIG. 9;

FIG. 13 is a left side elevation view of the pivotal nose pad of FIG. 9;

FIG. 14 is a right side elevation view of the pivotal nose pad of FIG. 9;

FIG. 15 is a top plan view of the pivotal nose pad of FIG. 9; and,

FIG. 16 is a bottom plan view of the pivotal nose pad of FIG. 9.
